CLAIM

The ornamental design for a swivel carabiner with slide buckle, substantially as shown and described.

DESCRIPTION

FIG. 1 is a perspective view of a swivel carabiner with slide buckle according to our new design.

FIG. 2 is a front elevational view thereof;

FIG. 3 is a back elevational view thereof;

FIG. 4 is a left side view thereof;

FIG. 5 is a right side view thereof;

FIG. 6 is a top view thereof;

FIG. 7 is a bottom view thereof; and,

FIG. 8 is a left side view thereof shown in a position of use with the carabiner part of the article swiveled to the right. The broken lines in the drawings depict portions of the swivel carabiner with slide buckle that form no part of the claimed design.
